FUEL INJECTOR

Herbert C. Edwards, Massillon, Ohio, assignor to
 The Timken Roller Bearing Company, Canton,
 Ohio, a corporation of Ohio

Application April 3, 1937, Serial No. 134,787

3 Claims. (Cl. 299—107.3)

This invention relates to fuel injectors for internal combustion engines, particularly compression-ignition oil engines. Its principal objects are to devise a simple and efficient injection nozzle of economical and durable construction and to obtain other advantages hereinafter appearing. The invention consists in the fuel injector and in the construction, combinations and arrangements of parts hereinafter described and claimed.

10 In the accompanying drawing, which forms part of this specification and wherein like symbols refer to like parts wherever they occur,

15 Fig. 1 is a central longitudinal section through a fuel injection nozzle embodying my invention, the discharge valve being shown in closed position,

Fig. 2 is a view of the outer or discharge end of said nozzle,

20 Fig. 3 is a cross-section on the line 3—3 in Fig. 1,

Fig. 4 is an enlarged fragmentary section, similar to Fig. 1, showing the discharge valve in closed position; and

25 Fig. 5 is a view, similar to Fig. 4, showing the valve in open position.

The fuel injector or nozzle shown in Figs. 1 to 5, inclusive, comprises a cylindrical nozzle member or portion 1 having an axial bore 2 extending therethrough and a plurality of circumferentially spaced longitudinally disposed fuel passageways 3 leading from an annular groove 4 in the inner or inlet end of said nozzle to an annular groove 5 in the outer or discharge end thereof, these grooves being disposed concentric to said axial bore. The axial bore 2 of the nozzle 1 is preferably flared, as at 6, at the outer end thereof; and it is provided at the inner end of said nozzle with an enlarged internally threaded portion 7 adapted to cooperate with an externally threaded head 8 of a pin 9 that extends through said bore beyond the flared outer end 6 thereof. The pin is formed with a collar 10 that seats against the bottom of the enlarged inner end portion 7 of the axial bore 2 of the nozzle and thus limits outward movement of said pin in said bore.

50 The nozzle 1 has a cap 11 threaded thereon that overlaps the outer end thereof and is provided opposite the outer end of the nozzle pin 9 with a flared central circular discharge orifice 12. Located opposite the discharge ends of the longitudinal fuel passageways 3 of the nozzle is a valve comprising one or more annular disks 13 of thin resilient metal that seat within a recess 14 provided therefor in the outer end of said

5 nozzle member and close the annular discharge groove 5 therein. These superimposed annular disks or plates are rigidly held at their outer margins only between the bottom of the recess 14 and an internal annular clamping rib 15 formed on the end wall of the nozzle cap 11. The free inner margin of the innermost annular disk bears resiliently against an annular valve seat 16 provided therefor on the discharge end of the nozzle between annular discharge groove 5 and the flared end 6 of the axial bore 2 and thus normally prevents the escape of fuel from said nozzle.

10 The nozzle pin 9 extends beyond the outer end of the nozzle member into the openings in the resilient disks 13 where it terminates in a flared end portion 17. As shown in the drawing, the opening in the innermost disk is made slightly larger than the portion of the pin therein to permit passage of the fuel therebetween when said disk is raised off its seat; and the openings 15 in the remaining disks are preferably of considerably larger diameter than the portion of the pin therein.

15 By the arrangement described, when the pressure of the fuel in the longitudinal fuel passageways 3, which are connected to a suitable fuel injection pump (not shown), is sufficient to overcome the pressure of the free inner margins of resilient disks 13 on the annular valve seat 16 of the nozzle, the innermost disk is forced away 20 from said seat, thereby permitting the fuel to pass between said disk and said seat and the annular space between the nozzle pin 9 and thence through the central opening in said plate. At the beginning of the opening movement of the 25 annular valve plate or disk, the fuel passes between the relatively narrow annular orifice between the nozzle pin and the opening in said disk, whereby only a small quantity of fuel is injected. Further movement of said disk brings 30 the opening in said disk opposite the small end of the nozzle, thereby gradually increasing the quantity of fuel discharged due to the increased width of the annular orifice between said disk and said pin. This gradual increase in the quantity 35 of fuel discharged prevents a sudden pressure increase in the engine cylinder and gives smoothness to the running of the engine. When the fuel pressure is reduced, the annular valve plate springs back into engagement with its annular 40 seat on the outer end of the nozzle, thereby stopping the fuel injection and preventing fuel dribble after the cessation of the injection. The spray angle and the rate of fuel discharge may be 45 varied by changing the shape of the portion of 45

the nozzle pin that cooperates with the valve disk opening to form the annular fuel discharge orifice.

What I claim is:

- 5 1. A fuel injector comprising a nozzle having an annular valve seat at its discharge end, and a resilient annular valve member having its outer marginal portion rigidly fixed to said end of said nozzle and its other marginal portion left free 10 and bearing resiliently against said annular valve seat, said end of said nozzle having a nozzle pin extending therefrom into the opening in said annular valve member and spaced from the edge of said opening to form an annular discharge orifice, said valve seat being formed integral with said nozzle and said nozzle pin being at all times clear of said valve member and said valve seat.
- 15 2. A fuel injector comprising a nozzle having a plurality of longitudinal circumferentially spaced fuel passageways and an axial bore all opening through the outer end thereof, a cap for said end of said nozzle having an axial discharge orifice, a valve member comprising a plurality of superimposed resilient annular plates having their outer margins clamped between said cap and said nozzle and their inner margins left free with the innermost plate in position to bear

resiliently against said end of said nozzle between the axial bore thereof and the discharge ends of said passageways, and a removable nozzle pin in said bore with its outer end portion disposed in the openings in said annular plates and spaced from the edges of said openings, the entire nozzle pin being at all times clear of said annular plates. 5

3. A fuel injector comprising a nozzle having an annular fuel discharge groove in the outer end thereof, an axial bore and an annular rib 10 forming an annular valve seat in said end of said nozzle between said annular groove and the adjacent end of said axial bore, a cap for said end of said nozzle having an axial discharge orifice, a valve member comprising a plurality of superimposed resilient annular plates covering said annular discharge groove with their outer margins clamped between said cap and said nozzle and their inner margins left free and the innermost plate in position to bear resiliently against 15 the annular valve seat on said end of said nozzle between the axial bore thereof and said annular discharge groove, and a pin in said bore with its outer end portion disposed in and cooperating with the openings in said annular plates to form an annular discharge orifice, the entire pin being at all times clear of said annular plates. 20 25
